UNITED STATES PATENT OFFICE.

FRANK P. KOBERT, OF AMITYVILLE, NEW YORK.

ELECTRIC RIVETING APPARATUS.

1,309,638.

Specification of Letters Patent. Patented July 15, 1919.

Application filed May 9, 1918, Serial No. 96,314.

Renewed December 11, 1918. Serial No. 266,364.

To all whom it may concern:

Be it known that I, FRANK P. KOBERT, a citizen of the United States, and residing at Amityville, L. I., in the county of Suffolk and State of New York, have invented certain new and useful Improvements in Electric Riveting Apparatus, of which the following is a specification, such as will enable those skilled in the art to which it appertains to make and use the same.

This invention relates to riveting apparatus and particularly to electric riveting apparatus, and the object thereof is to provide an apparatus of this class in which the plunger which operates as a riveter and which is driven by a crank shaft will have a cushioned or relief action which will accommodate it to changes in the strain on the crank shaft and on the plunger occasioned by changes in the character of the work piece or pieces or the thickness thereof, and which will prevent the breaking of the crank shaft or other parts of the apparatus; a further object being to provide an apparatus of the class specified with a vertically adjustable table or bed-plate on which the work piece or work piece holder is placed and which will also aid in accomplishing the object above set out.

The invention described and claimed herein is an improvement on that described and claimed in U. S. Letters Patent granted to me May 11, 1915, No. 1,139,300, and is fully disclosed in the following specification, of which the accompanying drawing forms a part, in which the separate parts of my improvement are designated by suitable reference characters in each of the views, and in which:

Fig. 1 is a side view of an apparatus involving my invention;

Fig. 2 a front view thereof;

Fig. 3 a sectional side view of the apparatus as shown in Figs. 1 and 2;

Fig. 4 a section on the line 4—4 of Fig. 3;

Fig. 5 a section on the line 5—5 of Fig. 3;

Fig. 6 a section on the line 6—6 of Fig. 3;

Fig. 7 a detail sectional view of an electrode holder and electrode which I employ;

Fig. 8 a bottom plan view of a carriage device which I employ, and which is shown in section in Fig. 3.

In the practice of my invention I provide a main frame *a* having a base *a*² and a for-

wardly directed top portion *a*³, and comprising side members *a*⁴ and transverse top frame members *a*⁵, *a*⁶ and *a*⁷ but my invention is not limited to any particular construction of the main frame.

Mounted in front of the bottom portion 60 of the main frame is a work support, table *b* having a bottom openwork body portion *b*² and this table in my improvement is made vertically adjustable.

The table *b* is connected with the side portions of the main frame by a tongue and groove construction as shown at *b*³ in Fig. 6, and passed through one of the side flanges thereof are set screws *b*⁴ which operate in connection with a corresponding part of the 70 main frame to hold the table at any desired point of adjustment.

The table *b* is made vertically adjustable by means of a vertically arranged shaft *c* which has a bearing in the bottom body 75 portion of said table and in the base *a*² of the main frame, and the upper end portion of said shaft is provided with a beveled gear *c*², and mounted at right angles to said shaft is a supplemental shaft *c*³ provided 80 with a pinion *c*⁴ which meshes with the gear *c*² and at its outer end with a hand wheel *c*⁵. The lower end of the shaft *c* is screw-threaded and passes through a correspondingly threaded bushing *c*⁶ mounted in the base *a*² 85 of the main frame and by means of this construction the table *b* may be raised or lowered and held at any desired point of adjustment, whenever desired.

Mounted in the central back portion of 90 the main frame and above the table *b* is a main crank shaft *d*, and mounted in the front top portion of the main frame is a vertically movable plunger carriage *e* which is held in position by vertical strips *e*² secured to the top portion of the main frame, and in the bottom portion of the plunger carriage is a curved space or chamber *e*³ which opens downwardly through a correspondingly curved slot *e*⁴, and the plunger 100 *f* is provided with a head *f*² movable through the space or chamber *e*³ and with a neck *f*³ movable through the slot *e*⁴.

Mounted between the main frame members *a*⁵ and *a*⁶ is an electrode carrier and 105 plunger guide *g* rotatably mounted on a shaft *g*², and the part *g* is provided with a forwardly extending and vertically ar-

ranged tubular head g^3 through which the plunger f passes and is vertically movable, and the head g^3 is provided with laterally directed keepers g^4 in which is mounted a 5 vertically arranged electrode support h which is cylindrical in form and provided at its lower end with an enlarged head h^2 with which the electrode i is connected, as clearly shown in Fig. 7, and as indicated in 10 Fig. 3.

The electrode support h is provided with a vertical slot at h^3 through which is passed an arm i^2 pivoted to the central portion of the part g at i^3 and provided at its outer 15 end with a handle i^4 , and the inner end of said arm is provided with a weight i^5 which normally holds the outer end of said arm and the electrode support h in their highest position.

20. The top of the electrode carrier and plunger guide g is provided with a backwardly directed extension g^5 to the bottom of which is secured a transverse block or plate j and beneath the rear end portion of the part 25 g^5 is a transverse shaft k provided at one end with a backwardly directed arm k^2 with which is connected a rod k^3 which is connected at k^4 with a treadle k^5 in the bottom of the frame, and mounted on the shaft k 30 is a clamp block k^6 of the usual form and which operates in connection with the block or plate j , as hereinafter described, and mounted in the sides a^4 of the main frame are stop screws k^7 which operate in connection with the part g^5 of the electrode carrier and plunger guide g to limit the 35 horizontal rotary movement of said part in the operation of the machine as herein-after described.

40. Mounted in the top portion of the main frame on a transverse shaft m is a rock beam m^2 which is secured to said shaft and provided at its front end with a head m^3 which fits in and operates in a corresponding 45 aperture e^5 in the vertically movable carriage e . The head m^3 is provided in the bottom thereof with a transverse recess m^4 which is semi-circular in cross section and in which is placed a transverse bar m^5 of 50 similar form in cross section, and to the bottom of which is secured a plate m^6 which is held in place by a transverse lock plate m^7 secured to the carriage e by screws m^8 .

The rear end of the rock beam m^2 is 55 provided with a fork-shaped head m^9 through which is passed a pin n on which is rotatably mounted a block bearing n^2 , and mounted on the crank of the shaft d is a split bearing n^3 and two rods o are mounted 60 in connection with the bearings n^2 and n^3 as shown. The rods o are threaded at their upper and lower ends and provided with nuts o^2 , and said rods are provided above the bearing n^3 with adjusting nuts o^3 above 65 which are placed flanged collars o^4 , and the

bearing n^2 is provided with downwardly directed hubs n^4 , and mounted on the rods o and resting on the flanged collars o^4 are strong spiral springs p , the tension of which may be adjusted by means of the nuts o^5 . 70

In the use of this machine the work-holder or holders having the usual electrodes are placed on the table b , as in the patent hereinbefore referred to, and said work holder or holders and said electrodes may 75 be of any preferred form and construction, and the electrodes are preferably water-cooled, and the parts to be riveted or connected are placed on said table and held by said holder or holders as in the patent 80 referred to.

In this invention, however, the electrode support or holder h which, in connection with the plunger f , is carried by the head g^3 of the electrode carrier and plunger guide 85 g as in the patent referred to, is provided with a swiveled head h^2 which is mounted on a reduced extension h^4 of the part h and is held in connection therewith by a transverse plate or bar h^5 through which 90 is passed a screw h^6 , and with this construction the electrode i has a swiveled connection with the support h of which the head h^2 of said holder forms a part, and said electrode i may be freely turned on the 95 support h .

The electrode i consists of a top part i^1 and a bottom part i^7 , and the top part i^1 is connected with the part h^2 by screws or 100 bolts i^8 which are insulated from the part h^2 , and said part h^2 is insulated from the part i^7 , as clearly shown in Fig. 7.

The bottom part i^7 of the electrode i is cylindrical in form and provided with a spiral groove i^9 inclosed by a sleeve i^{10} provided with ports or passages i^{11} and i^{12} , and the port or passage i^{11} communicates with the top member of the spiral groove i^9 , while the port or passage i^{12} communicates with the bottom member of said groove and 110 water supply and discharge tubes or pipes i^{13} and i^{14} are connected with the sleeve i^{10} or the ports or passages i^{11} and i^{12} therein, and by means of this construction the electrode i may be kept cool or prevented 115 from overheating when in use.

The operative part of the electrode i consists of a plug r having a tapered shank r^2 which is driven into a corresponding aperture in the bottom part i^7 of the electrode, and the top part i^1 of the electrode is extended at one side and connected therewith is a keeper s in which is secured a conductor s^2 which, in practice, is connected in a transformer in the usual manner, or as 120 shown and described in the patent referred to. 125

The operation will be similar to that of the patent referred to, and will be readily understood by those familiar with the op- 130

eration of this class of devices, the distinctive features in this case being, as hereinbefore stated, the vertically adjustable table *b*, the cushioned or relief action of the 5 plunger which is secured by means of the beam *m*², its connection with the carriage *e* and its connection with the crank shaft *d* which involves the springs *p*, and the rods *o* and their connections and also in the electrode *i*, or the details thereof, the movement 10 of the electrode carrier and plunger guide *g* and the operation of the plunger and the electrode support *h* being the same as in said patent.

15 In the construction herein shown and described, the rods *o* are freely movable through the bearing or bearing block *n*², and the power transmitted by the shaft *d* to the plunger through the plunger carriage 20 *e* is transmitted by or through the springs *p* and the beam *m*² and the said plunger is thus given a cushioned or relief action, and will adapt itself to varying thicknesses of 25 work pieces, or pieces to be connected, without danger of straining the apparatus or breaking the crank shaft, and when this feature is taken in connection with the vertically adjustable table *b* the number of 30 work pieces or pieces to be connected or riveted together may be increased, as will be readily understood.

The statement that the electrode carrier and plunger guide *g* operates, or is operated in the same manner as in the patent 35 referred to is limited in this construction by the use or operation of the parts *j*, *k*⁶ and *k*⁷, which parts operate to prevent the operation 40 of the trip mechanism, consisting of the treadle *k*⁵, rod *k*³, the arm *k*² and the shaft *k*, and if the clamp block *k*⁶ is permitted to pass the plate *j* by the proper 45 alignment of the electrode carrier and plunger guide *g*, the plunger *f* will be operated, but if the part *g* should not be moved 50 into the proper position to bring the plunger *f* into alignment with the work piece, the clamp block *k*⁶ would strike the bottom of the plate *j* and prevent the operation of the apparatus by reason of the fact that the 55 treadle *k*⁵ could not be depressed.

In the accompanying drawing, the main crank shaft *d* is provided with a fly-wheel *d*², but the means for operating said shaft are not shown for the reason that they form 55 no part of this invention, nor is the means for controlling the operation of the crank shaft for a similar reason, and all these parts may be of the usual or any preferred construction, and changes in and modifications 60 of the details of the improvements herein shown and described may be made, within the scope of the appended claims, without departing from the spirit of my invention or sacrificing its advantages.

65 It will be observed that the plunger *f* and

the electrode carrier *h* have a vertical movement through the head of the swinging member *g*, and the movements of these parts in the operation of the machine are apt to tangle and twist, and even disconnect or 70 break the water circulating tubes *i*¹³ and *i*¹⁴ and the conductors or leads *s*² which are connected with the electrode *i*, and it is for this reason and in order to prevent this result that the said electrode is provided with 75 a swiveled connection with its support *h*.

Having fully described my invention, what I claim as new and desire to secure by Letters Patent, is:—

1. In an apparatus of the class described, 80 a frame, a vertically movable plunger carriage, a plunger suspended from said carriage, a crank shaft, a rock beam mounted between the crank shaft and the carriage, and spring devices mounted between the 85 crank shaft and the rock beam and through which and said beam the power of the crank shaft is transmitted to the plunger.

2. In an apparatus of the class described, 90 a frame, a vertically movable plunger carriage, a crank shaft, a rock beam mounted between the crank shaft and the carriage and the front end of which is in operative connection with said carriage, a bearing 95 mounted on the crank shaft, another bearing pivoted in the rear end of the rock beam, rods mounted in the crank shaft bearing and passing loosely through the bearing in the rear end of the rock beam, and springs 100 mounted on said rods and on which the last named bearing rests.

3. In an apparatus of the class described, 105 a frame, a vertically movable plunger carriage, a plunger suspended from said carriage, a crank shaft, a rock beam mounted between the crank shaft and the carriage and the front end of which is in operative connection with said carriage, a bearing mounted on the crank shaft, another bearing 110 pivoted in the rear end of the rock beam, rods mounted in the crank shaft bearing and passing loosely through the bearing in the rear end of the rock beam, springs 115 mounted on said rods and on which the last named bearing rests, and means for adjusting 120 the tension of said springs.

4. In a machine of the class described, a frame, a vertically movable plunger, a rock beam pivoted in said frame and one end of 120 which is in operative connection with said plunger, and means for connecting the other end of said beam to the crank shaft and for cushioning the operation of said shaft.

5. In a machine of the class described, a 125 horizontally movable member, a plunger vertically movable through one end of said member, an electrode holder also movable through said end of said member and parallel with the plunger, and an electrode 130

having a swiveled connection with said holder.

6. In a riveting apparatus of the class described, a frame, a plunger carriage vertically movable therein, a plunger connected with said carriage and movable transversely therein, an electrode carrier and plunger guide movable transversely of said carriage and through which the plunger is movable and an electrode support mounted in and movable through said carrier and plunger

guide and parallel with the plunger and provided with a swiveled electrode.

In testimony that I claim the foregoing as my invention I have signed by name, in ¹⁵ presence of the subscribing witnesses, this 6th day of May, 1916.

FRANK P. KOBERT.
